UNITED STATES PATENT OFFICE.

STEPHEN S. NEWTON, OF BINGHAMTON, NEW YORK.

BOTTLE-STOPPER.

SPECIFICATION forming part of Letters Patent No. 251,922, dated January 3, 1882.

Application filed June 23, 1881. (Model.)

To all whom it may concern:

Be it known that I, STEPHEN S. NEWTON, a citizen of the United States, residing at Binghamton, in the county of Broome and State of New York, have invented certain new and useful Improvements in Bottle-Stoppers; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 is a vertical section of a stopper containing my invention. Figs. 2, 3, and 4 are vertical sections of modifications of parts of the invention. Fig. 5 is a plan view, partly in section, of Fig. 2. Fig. 6 is a similar view of Fig. 20 3; and Figs. 7 and 8 are detached views, in perspective, of the stopper shown in Fig. 4.

In all of the figures, A is the cork-tube section, having a flange, B, adapted to cover the cork D and mouth of the bottle.

25 E is a screw-threaded tube-section engaging with threads on the cork-tube and rising and falling thereon, and provided with a valve, C', which, when screwed down, closes an opening, a, in said cork-tube, to prevent liquid being 30 discharged through tip e.

e' is a spur projecting horizontally from tube-section E and engaging with a stop, a³, to limit the rotation of said tube when it is being screwed upon cork-tube A. In Fig. 1 this stop a³ is formed 35 on the upper end of the cork-tube A, a portion of which is cut away, as indicated at a² a³. In Figs. 2, 3, 5, 6 the stop projects upwardly from flange B' in the path of spur e', while in Figs. 4 and 8, b is a spiral groove or slot in flange B', 40 the wall at the end of which forms said stop a³. In practice I prefer a groove upon the inner face of flange B', the upper edge of the flange being bent outwardly a little to facilitate entering spur e' into the groove b, and afterward 45 closed in to retain the spur.

In Fig. 1 the opening a is formed in the flange or plate which separates the lower part of cork-tube from its upper enlarged part, and the valve C' consists of the flat lower end of the 50 tube-section E, which is closed at this point, except that it has one or more eccentric ports, e.

a' is a packing-washer, against which the valve C' abuts when it is screwed down. In Fig. 2 the valve C' is attached to the lower end of tube-section E, and is by preference conical in form, the inner surface of the lower end of the cork-tube being correspondingly shaped. In Figs. 3 and 4 the valve C' is arranged within the tube-section, and near its upper end, leaving ports or glands on two or more sides, and 55 engages with the upper end of the cork-tube.

e' is a thumb-plate having a milled edge, by which to rotate the tube-section E and screw it up or down.

It will of course be understood that the function of the spur e' and stop a³ is to limit the rotation of tube-section E when being rotated in the direction necessary to raise the valve from the opening a, the rotation in the opposite direction continuing until the opening a 70 has been closed.

Of course the washer a' might be dispensed with and the lower flat end of the tube-section in Fig. 1 made to close the opening a; but I prefer the construction shown.

I have shown in my Patent No. 186,364, for oilers, dated January 16, 1877, a construction of valve-seat, rising and falling valve attached to screw-threaded discharge-tube, and stops which limit the rotation of the tube, which in 75 some respects resemble the construction shown in this case; but the invention shown in that patent would not be desirable as applied to the bottle-stopper in this case, because it would necessitate recessing or cutting away the outer 80 edge of flange B to form the stop, and would consequently necessitate extending the spur e horizontally across the upper face of said flange, and then bending it downward to engage with the stop, which it would be impracticable to do. 85 This difficulty I avoid in my present construction by supporting the stop above the plane of flange B, and in close proximity to the rotating discharge-tube, and then projecting the spur horizontally from the discharge-tube, so 90 that the plane in which it rotates shall be intersected by the upwardly-projecting stop. By this construction and arrangement of parts I am also enabled to hide both the spur and the stop from view, as shown in Fig. 4.

What I claim is—

1. In a bottle-stopper, the combination of a

screw-threaded tube-section attached to the flange B, and provided with a valve-seat, a screw-threaded tube-section engaging therewith and provided with a valve and with a horizontally-projecting spur, and a stop supported above the flange B and in the lateral path of the spur, substantially as set forth.

2. In a bottle-stopper, the combination of a screw-threaded tube-section attached to the flange B, and projecting both above and below said flange and provided with a valve-seat, a screw-threaded tube-section engaging therewith and provided with a valve and with a horizontally-projecting spur, and a stop formed 15 on the upwardly-projecting flange which is attached to said flange B, and in the lateral path of the spur, substantially as set forth.

3. In a bottle-stopper, the combination of a screw-threaded tube-section attached to the flange B, that portion which projects above the 20

flange being screw-threaded internally and provided with a valve-seat, an externally screw-threaded tube-section engaging therewith and provided with a valve and with a horizontally-projecting spur, and a stop formed on the upper end of the cork-tube and in the lateral path of the spur, substantially as set forth. 25

4. The combination, in a bottle-stopper, of the internally screw-threaded tube-section projecting above the flange B, and having a central opening, a, with the externally screw-threaded tube section E, closed at its lower end, and having one or more eccentric ports, c, substantially as set forth. 30

In testimony whereof I affix my signature in presence of two witnesses. 35
